UNITED STATES PATENT OFFICE.

JULIUS HOCK, OF VIENNA, AUSTRIA.

CALORIC ENGINE.

SPECIFICATION forming part of Letters Patent No. 231,488, dated August 24, 1880.

Application filed June 7, 1880. (No model.)

To all whom it may concern:

Be it known that I, JULIUS HOCK, residing at Vienna, in the Empire of Austria, and a subject of the Emperor of Austria, have invented certain Improvements in Caloric Engines, of which the following is a specification.

Figure 1 is a side view, partly in section, of my improved caloric engine. Fig. 2 is a section through the fire-box; Fig. 3, an enlarged end view, partly in section, of the air-pump, taken on the plane of the line *c c*, Fig. 4. Fig. 4 is a longitudinal section of same. Figs. 5, 6, 7, and 8 are detail sectional views, herein-after more clearly referred to.

15 This invention relates to caloric engines, wherein air compressed by a pump is forced through a closed fire-box or combustion-chamber, in order partly to support the combustion of fuel and partly to pass in a heated condition, together with the gaseous products of combustion, into the working-cylinder, the piston of which is propelled thereby.

One of the present improvements relates to the cooling of the air undergoing compression, 25 in order to prevent the loss of useful effect that otherwise results from the increase of temperature due to the compression.

For this purpose the air-compressing pump A has at its end or ends a small orifice, *a*, Figs. 3 and 4, communicating by a pipe or channel, *b*, with a water-tank, B, situated at a moderate height above the air-pump, so that the water will flow down by gravity through the pipe *b* and enter the cylinder A through the said orifice. In close contiguity to such orifice is a second orifice, *c*, formed obliquely to the first one, and communicating by a passage or pipe with any convenient part of the combustion-chamber, or with passages C, containing the 35 air under pressure, so that a small jet of air will enter the cylinder through such orifice, and in impinging obliquely upon the small jet of water entering the pump-cylinder will blow this into spray, which, in mixing intimately 40 with the air that is undergoing compression in the pump, will take up heat therefrom. Steam will thus be formed at the same time by the action of the heat on the water-spray, and this steam will pass away, together with the air, to 45 do duty in the engine-cylinder. This arrange- 50

ment of pipe *b* and orifice is at each end of the cylinder A, as indicated in Fig. 1.

In order to prevent the water from continuing to run into the air-compressing cylinder when the engine is not at work the supply is 55 automatically stopped by providing on the supply-pipe *b* a cock or valve, *f*, acted upon by a weight, *d*, or spring, tending to close it, and also, in the contrary sense, by a piston, *e*, in a small cylinder communicating with the 60 passages or chamber, for compressed air, so that when, on the starting of the engine, a certain air pressure has been attained, this, in acting on the small piston, will force open the valve or cock *f*, and allow the water to enter 65 the air-compressing cylinder.

In order to supply a further quantity of steam to mix with the air and gases under pressure, so as to increase the useful effect of the engine, one or more jets of water, *g*, Fig. 2, are forced in the 70 form of spray at one or more points into the chambers or passages D, containing the heated air and gases under pressure, such introduction of water being effected in regulated quantities by means of a pump, *h*. The water is, 75 by preference, forced through a narrow adjustable annular orifice formed by the insertion into a circular opening of a conical plug, *i*, at the end of a rod that can be screwed more or less forward, so as to increase or decrease the annular space between the plug and the opening.

One such jet of water-spray may advantageously be introduced into the closed combustion-chamber D of the engine, and another 85 in the pipe E, Figs. 6 and 8, leading from the fire-box to the working-cylinder. In the latter case there are provided in the pipe, just below the said jet, a number of wire-gauze screens, *j*, placed one above the other, so that 90 the water-spray, in falling upon and passing through such screens, heated to a considerable extent by the gases in the pipe, will rapidly be converted into steam, and at the same time be mixed intimately with the air and gases 95 that are also passing through the screens. As these gases carry with them a certain amount of dust from the fuel in the fire-box, such dust, as also the solid matter held suspended in the water, will be intercepted by 100

the screens, which are removed from time to time to clear them of such accumulated deposits. To facilitate such removal the pipe is provided at the point where the screens are situated with a side opening, closed hermetically by a cover, *k*, Fig. 8, secured by screws *l*, the screens being merely placed loosely one above the other in the pipe, which has shoulders or lugs *m* for supporting them.

10 It will be evident that a certain relation will have to be maintained between the quantity of air introduced into the fire-box and the quantity of water mixed therewith for the production of steam. Upon the quantity of air will 15 depend the quantity of fuel that can be burned and heat produced, and upon this depends, again, the quantity of water that can be converted into steam of definite temperature; and thus it follows that if the temperature is to be 20 maintained approximately constant, the proportion between air and water supply once determined must also be constant. This is effected by regulating the pressure in the chambers and passages containing the air and gases 25 under pressure, as follows: The speed of the engine is regulated by causing a governor to effect the opening of the admission lift-valves to the working-cylinder for a greater or shorter length of time by means of revolving and 30 sliding cams *n*, Fig. 1, which open the valves against the action of springs. On the load on the engine decreasing the cut-off is consequently caused to take place earlier, the effect of which would be to produce an increase of 35 pressure in the chambers and passages containing the air under pressure if the compressing-cylinder and water-jets continued in full action. To prevent this a piston, *o*, in a small cylinder, *p*, Figs. 1, 5, and 7, is acted upon in 40 one direction by the air-pressure in the chambers or passages, and in the contrary direction by a weight or spring, *q*, which is so adjusted that as soon as the air-pressure exceeds the desired limits the piston is moved in opposition to the weight or spring, and is thereby 45 made to act on levers that keep the supply-valves of the compressing-pump closed, and also on other levers, *r*, that close the cocks or valves on the supply-pipe of the water-jets 50 until the pressure is again reduced.

The gearing by which the force-pump for the water-jets is worked from the engine is

so arranged as to be readily disconnected, so that for starting the engine the pump-lever can be worked by hand, in order to force sufficient water into the fire-box to produce steam of the requisite pressure to move the working-piston. 55

For larger engines, and particularly those that require to be maintained constantly in 60 action for a considerable length of time, such as marine engines, two or more separate fire-boxes or combustion-chambers are provided, and the air pipes and passages leading from the compressing-pump, as also those leading 65 to the working-cylinder, are made to communicate with both or all the combustion-chambers, but are provided with valves so arranged that the one or the other combustion-chamber can be cut off from the communications, for the 70 purpose of cleansing and repair, without interfering with the action of the engine.

I am aware that a screen submerged in water in a boiler has already been used for dividing the heated gases that bubble up through 75 the water. This I do not claim.

I claim—

1. The combination, in a caloric engine, of the air-pump *A*, having the jet-orifice *a* and the inclined air-orifice *c*, with the water-supply 80 pipe *b*, and with the air-chamber *C*, substantially as herein shown and described.

2. The combination of the hot-air chamber *D* or its pipe *E* with one or more jet-pipes, *g*, pumps *h*, and regulating-plugs *i*, substantially 85 as herein shown and described.

3. In a caloric engine, the combination of the screens *j* with hot-air pipe *E*, which leads from the fire-box to the working-cylinder, and with the jet-pipe *g*, for discharging a jet of 90 water upon said screens, substantially as herein shown and described.

4. The combination, with the compressed-air chamber, of the cylinder *p*, weighted piston *o*, and levers *r*, for automatically actuating the cocks in the water-supply pipe, substantially as herein shown and described. 95

In testimony whereof I have signed my name to this specification in the presence of two subscribing witnesses.

JULIUS HOCK.
